Pending U.S. Appl. No. 29/498,332, filed Aug. 1, 2014.

Primary Examiner — Robert M Spear*Assistant Examiner* — Ryan Harvey(74) *Attorney, Agent, or Firm* — Tyson B. Benson; Advent, LLP**CLAIM**

The ornamental design for a motorcycle stirrup, as shown and described.

DESCRIPTION

FIG. 1 is an isometric view of a motorcycle stirrup.
FIG. 2 is a front elevation view of the motorcycle stirrup of FIG. 1.
FIG. 3 is rear elevation view of the motorcycle stirrup of FIG. 1.
FIG. 4 is a left side elevation view of the motorcycle stirrup of FIG. 1.
FIG. 5 is a right side elevation view of the motorcycle stirrup of FIG. 1.
FIG. 6 is a top plan view of the motorcycle stirrup of FIG. 1.
FIG. 7 is a bottom plan view of the motorcycle stirrup of FIG. 1; and,
FIG. 8 is an isometric view of a motorcycle stirrup shown in use on a portion of a motorcycle.
Portions of FIGS. 1 through 7 and the motorcycle in FIG. 8 are shown in broken and dash-dot-dot lines illustrating portions of the article and environmental subject matter, respectively, that form no part of the claimed design.
